UNITED STATES PATENT OFFICE

2,452,773

CUTTING TABLE

David Levin, Brooklyn, N. Y.

Application June 1, 1946, Serial No. 673,865

13 Claims. (Cl. 161—73)

1

This invention relates to a cutting table, and particularly such a table over which a mechanical cutting tool is moved to cut, in a single operation, a plurality of superimposed plies of cloth.

An object of the invention is to provide such a table in which the cloth may remain substantially flat at all times during the cutting operation.

A further object is to provide such a table in which the cutting tool may readily be moved in all directions over the surface of the table.

Another object is to provide such a table in which parts of the table surface automatically move out of the way of the cutting tool as the latter is moved, and in which the cloth remains adequately supported at all times.

A further object is to provide certain improvements in the form, construction and arrangement of the several parts whereby the above named and other objects may effectively be attained.

A practical embodiment of the invention is shown in the accompanying drawings, wherein:

Fig. 1 represents a top plan view of the table, parts being broken away;

Fig. 2 represents a longitudinal vertical detail section taken on the line II—II of Fig. 1, looking in the direction of the arrows;

Fig. 3 represents a transverse vertical detail section taken on the line III—III of Fig. 1, looking in the direction of the arrows;

Fig. 4 represents an end elevation of the parts shown in Fig. 3, viewed from the right of Fig. 3;

Fig. 5 represents a view corresponding to Fig. 3 with the parts in a different position;

Fig. 6 represents a detail modification of the parts shown in Fig. 4;

Fig. 7 represents a transverse vertical detail section taken on the line VII—VII of Fig. 1, looking in the direction of the arrows, certain parts being omitted;

Fig. 8 represents a vertical section taken on the line VIII—VIII of Fig. 7;

Fig. 9 represents a vertical section taken on the line IX—IX of Fig. 7;

Fig. 10 represents a vertical section taken on the line X—X of Fig. 7, and

Fig. 11 represents a section corresponding to Fig. 3 showing a modified arrangement of certain brackets.

In general, the table comprises rows of horizontally spaced L-shaped supports, pivotally mounted on the side frame members of the table and arranged to constitute, in their upper positions, an adequate support for a lay of cloth to be cut. A carriage which is movable lengthwise of the

table carries an endless band (movable transversely of the table) in which is mounted a suitable cutting tool, freely rotatable horizontally. The upper run of the endless band is in the same horizontal plane as the surfaces of the L-shaped supports in their upper positions. The parts are so coupled, through cams and followers along the sides of the table, that longitudinal motion of the carriage causes the supports to swing successively to their lower positions out of the way of the carriage and to be returned to their upper positions as soon as the carriage has passed, the lay of cloth being supported on the upper run of the endless belt in the area where the carriage has caused the supports to be depressed. The table thus retains an effective continuity of surface while the cutting tool is moved at will in any direction and cuts the cloth without lifting it out of its normal horizontal position.

Referring to the drawings, the table includes side frame members 1, 2, end frame members 3 and legs 4 of a suitable length. The right and left sides of the table, as viewed in Fig. 1, are duplicates (except for the staggered arrangement of the supports) so that the description of either side is applicable to both. Above the side frame members 1, 2 are horizontal tracks 5. The member 2 carries a plurality of pairs of upstanding brackets 6 in which the L-shaped supports 7 are pivotally mounted as shown at 8 (Figs. 2—5). Each support includes an upper horizontal part 9 (which may be recessed at regular intervals as shown at 10), a vertical arm 11, an arcuate extension 12 having notches 13 and 14 spaced 90° apart around the pivot point 8, a counterweight 15 adapted to keep the whole support assembly approximately in equilibrium and a cam follower 16 adjacent the pivot point and extending, for instance, downward when the support is in its upper position.

Guide bars 17 extend vertically from the brackets 6 to the track 5, and latch members 18 are slidably mounted on these bars so that they may be moved into and out of engagement with the notches 13 and 14. Each latch member carries a cam follower 19 which projects horizontally outward. The cam followers 16 and 19 may be in the form of pins or rollers.

The longitudinally movable carriage includes a pair of tracks 20 extending across the table and mounted on carriage frames 21, which fit horizontally and vertically on the tracks 5; suitable anti-friction devices such as wheels or rollers 22, 23 assure easy movement of the carriage along the tracks 5.

Cam supporting brackets 24 extend downwardly from the carriage frames 21, said brackets carrying a pair of latch cams 25, 25, and extending around the side frame member 2 and up between the members 1 and 2 to carry the support-actuating cams 26, 26. The cams 25 are in the form of curved grooves, low at the ends and high in the middle, and are so disposed as to engage the cam followers 19 to raise and lower the latch members 18 as the carriage is moved. The cams 26 are in the form of approximately helical grooves extending around an arc of 90°, and are so disposed as to engage the cam followers 16 to rotate the supports 7 between their upper and lower positions (Figs. 3 and 5) as the carriage is moved. The cams 25 and 26 must naturally be placed so that the latch members 18 are held out of engagement with the notches 13 and 14 while the supports are being rotated or rocked; that is, the cams 25 must release the latch before the cams 26 can cause rotation in either direction, as by disposing the active helix of the cams 26 opposite the high middle part of the cams 25.

The tracks 20 have slots or grooves 27 near their upper edges and shoulders 28 spaced somewhat below the slots or grooves. A cutting tool mounting 29, provided with wheels or rollers 30, is arranged to be movable between the tracks and supported by the shoulders 28, this mounting including a circular turn-table 31 to which a cutting tool (not shown) is secured so as to be freely rotatable in all directions. The tool may be of the type exemplified by Ogden Patent No. 2,343,202, issued February 29, 1944, or may preferably be of the type in which cutting blades are mounted on the links of an endless chain, as in C. E. Clark Patent No. 1,309,317, issued July 8, 1919.

In either case the usual base of the tool is eliminated and the tool is secured directly to the turn-table 31. As shown in Figs. 1, 2, 7 and 8, the turn-table is slotted as at 32 so that the cutting blades can pass below the table surface.

The mounting 29 forms part of an endless belt made up of the blocks 33, hinged together at 34, and provided with pins or rollers 35 which project into the grooves 27, as shown in Fig. 9. This belt is supported at its ends by the sprocket wheels 36 journaled on brackets 37 which are mounted on the carriage frames 21, the sprockets engaging with the rollers 35 of the blocks at the ends of the belt. The carriage is also provided with auxiliary supporting fingers 38, which may be mounted at the top edge of the tracks 20, and which project lengthwise of the table at intervals across the table corresponding to the recesses 10 in the hinged supports 7. These fingers extend from the carriage a distance at least somewhat greater than the interval between adjacent supports, and the outer ends of the fingers are disposed slightly below the level of the top surface of the supports.

In operation, a lay of cloth to be cut, comprising any suitable number of plies piled up within the thickness limit of the cutting machine, is placed on the table; the supporting surface of the table being made up of the parts 9 of the individual supports in their upper positions, supplemented by the fingers 38 and the endless belt formed by the blocks 33. The cutting machine, mounted on its turntable 31, is then moved, by hand or otherwise, in any desired direction through the lay, traveling transversely of the table on the tracks 20 of the carriage and traveling lengthwise of the table with corresponding lengthwise movement of the carriage. The cut-

ter may be moved in a straight, curved or angular line as may be required, for instance, by a cutting pattern for the particular lay being cut.

In the case of a movement having a transverse component it will be evident that a continuous lay-supporting surface is formed at all times by the blocks 33, mounting 29 and turntable 31, regardless of how the latter may be moved.

In the case of motion having a lengthwise component, the lay-supporting surfaces of the carriage, including the fingers 38, automatically substitute themselves for the parts 9 of the hinged supports as the carriage is moved. As the carriage advances its front pair of cams 25 and 26 engage a corresponding pair of followers 19 and 16, respectively; cam 25 lifts the latch member 18 on which follower 19 is mounted out of engagement with notch 13, cam 26 then rotates through a 90° turn the support 7 on which the follower 16 is mounted, and upon completion of this rotation the cam 25 lowers the latch 18 into engagement with the notch 14 to hold the support in its depressed position (Fig. 5). This procedure is repeated as the carriage approaches successive supports, at least two such supports on each side of the table being depressed at any position of the carriage, as shown in Figs. 1 and 2. As the carriage starts to pass beyond one of the supports depressed beneath it, the rear pair of cams act in a reverse manner to raise the support; the rear cam 25 releasing the latch while the corresponding rear cam 26 swings the support to its upper position where it is again latched.

The supports on the two sides of the table are staggered so that there can be no interference when they are moving and so that resistance to motion of the carriage (resulting from friction in the cams, inertia of the supports, etc.) will be distributed as evenly as possible.

In Figs. 3, 4 and 5 the supports are shown as being balanced by counter-weights 15 and Fig. 7 shows the brackets 24 shaped to allow room for these counterweights. The latter may, however, be replaced by suitable springs, for instance the torsional springs 39 shown in Fig. 6, in which case the bracket 24 can be made somewhat more compact, if desired. In the further modification shown in Fig. 11 the supports 7 are pivoted in brackets 40 mounted on the side frame member 1, the member 2 being eliminated and the bracket 24 being replaced by a short bracket 41. In this case it is assumed also that springs (not shown) are used instead of counter-weights.

The table can be made of any desired length, with more than one carriage unit if necessary, and of a width sufficient for any normal requirements. The supports may not have to be depressed through a full 90° so long as they move far enough to clear the lower run of the endless belt on the carriage. If the supports are so balanced as to stay depressed by gravity, the notches 14 may be omitted together with the inner half of each cam 25. The horizontal spaces between adjacent supports can be made narrower, resulting in a more nearly continuous supporting surface, by widening the parts 9 or by locating the supports closer together, or both, in cases where this may seem desirable.

It will be understood that various other modifications can be made in the form, construction and arrangement of the several parts without departing from the spirit and scope of the invention; and hence I do not intend to be limited to details herein shown or described except as they

may be included in the claims or required by disclosures of the prior art.

What I claim is:

1. A cutting table comprising, a frame, a plurality of supports pivotally mounted in the frame, releasable means for holding the supports in work-supporting position, a carriage extending across the frame and movable longitudinally thereof, portions of the supports and the carriage top lying in a single plane to constitute a work-supporting table surface, a cutting tool mounting on the carriage, and means on the carriage moving the supports out of the path of said carriage adjacent the carriage on the side toward which it is moved and returning the supports to said plane adjacent the carriage on the opposite side thereof.

2. A cutting table according to claim 1 which includes means on the carriage actuating the support-holding means.

3. A cutting table according to claim 2 in which the means actuating the support-holding means is a cam and in which the support-moving means is a cam.

4. A cutting table according to claim 1 in which the carriage top is horizontally movable with respect to the carriage.

5. A cutting table according to claim 1 in which the carriage top is horizontally movable with respect to the carriage, and in which the cutting tool mounting forms part of said movable top.

6. In a cutting table of the character described having a supporting surface for the lay of material to be cut, a movable carriage including tracks extending across the table, an endless belt having its upper run guided by said tracks in the plane of the supporting surface, and a cutting tool mounting constituting part of said endless belt.

7. A table according to claim 6 in which the cutting tool mounting comprises a turn-table having its upper surface in the plane of the ma-

terial-supporting surface and being provided with an opening in which a cutting tool may pass below the level of said plane.

8. In a cutting table of the character described having a supporting surface for the lay of material to be cut, a plurality of pivotally mounted supports each comprising a horizontal part, a vertical arm, an arcuate part disposed around the pivot point and means for counterbalancing the support.

9. A table according to claim 8 in which the arcuate part is provided with at least one notch adapted to engage a holding means.

10. A table according to claim 8 in which the horizontal part is transversely recessed.

11. A cutting table of the character described in which the supporting surface for the lay of material to be cut comprises, the horizontal parts of a plurality of pivotally mounted supports, the upper run of an endless belt extending across the table, and a cutting tool mounting constituting part of said endless belt, said supporting surface elements having their upper surfaces substantially in the same plane.

12. A cutting table according to claim 11 in which the said horizontal parts of the supports are transversely recessed.

13. A cutting table according to claim 11 in which the said horizontal parts of the supports are transversely recessed, and which includes auxiliary supporting fingers extending from points adjacent the endless belt into the recesses of adjacent supports.

DAVID LEVIN.
